UNITED STATES PATENT OFFICE.

MAURICE VAN MARCKE DE LUMMEN, OF COLOGNE, GERMANY.

ROASTING-FURNACE.

1,067,045.

Specification of Letters Patent.

Patented July 8, 1913.

Application filed June 11, 1912. Serial No. 702,951.

To all whom it may concern:

Be it known that I, MAURICE VAN MARCKE DE LUMMEN, subject of the King of Belgium, residing at Cologne - on - the - Rhine, 5 Germany, have invented new and useful Improvements in Roasting-Furnaces, of which the following is a specification.

This invention relates to roasting furnaces and more particularly to tier furnaces for the roasting of pyrites and other sulfur compounds. In furnaces of this kind various devices have been proposed for counteracting the production of dust. These devices however only inefficiently fulfill requirements and in practice have proved to be more or less useless. It has for instance been attempted to counteract the production of dust by the provision on the agitating arms of screens rotating with the arms so as to close the drop openings against the hot gas current, or the ore is caused to pass through closed hoppers or along open inclined surfaces. According to another method the ore and the heating 20 gases were caused to pass through separate vertical passages. The use of the rotary screens referred to is practically impossible owing to frictional difficulties caused by the necessary tight closure of the tiers or stages. 25 Moreover in order to prevent the production of dust a relatively great length of screen is required whereby the traveling velocity of the heating gases and consequently the danger of dust being produced are increased. 30 The passage of the material through closed oblique hoppers or through vertical tubes has the drawback that such passages are liable to be readily clogged by ore adhering to their sides, thereby causing the following 35 ore to seek a different path and thus giving rise to the production of dust. Moreover such hoppers or passages cannot be readily cleaned during working.

Now the present invention relates to a 40 screen arrangement for mechanical roasting furnaces, whereby all the drawbacks above mentioned are readily removed.

The characteristic feature of the invention consists in the provision beneath each 45 drop opening, formed with a downward incline in known manner, of an open guide or plate having the same angular inclination and being attached by means of an arm to the rotary shaft or spindle of the agitating 50 device. This guide extends close to the next lower tier and enables the ore to pass readily

and without the production of dust into the lower tier. At the same time the guide protects the downwardly traveling layer from being directly attacked and penetrated 60 by the upwardly passing hot gas current in the furnace.

The upper edge of the guide or screen which is secured to the hollow shaft of the agitating device is caused to rotate in an annular member or ring which is protected against the adhesion of the ore and which moreover prevents the gas current from striking the roasting material at the point where it passes from one tier to the other 70 and at the same time enables the guide or screen to rise in the event of the hollow shaft expanding.

A preferable form of the invention is shown in the accompanying drawings in 75 which—

Figure 1 illustrates an axial longitudinal section of a roasting furnace provided with the improved device. Fig. 2 is a cross section of Fig. 1 on the line A—B. Fig. 3 80 illustrates parts of Fig. 1 and the main features of the invention on an enlarged scale and Figs. 4 and 5 show in detail the mode of attaching the screen or guide arrangement to the hollow shaft of the agitating device. 85

According to this invention beneath each oblique drop opening *a*, through which the ore is caused to pass from one grate on to the next, is a guide or screen *b* having the same angular inclination. This guide or 90 screen consists of an oblique plate which is secured to the rotary shaft *c* in a suitable manner as will be hereinafter more fully described. The screen *b* extends down close to the surface of the next lower stage and in 95 this way acts as a guide for the ore in its passage to the lower stage without any possibility of dust being stirred up. As shown in Figs. 1 and 2 the screen plates *b* are arranged directly vertically beneath two agitating arms or scrapers *l* which rotate in the next higher tier, so that the screens appear always beneath the drop openings at the same moment in which the arms *l* in the upper tier sweep the ore into the drop openings. The arms *m* of the tier in which the screen plates are arranged are secured to the shaft *c* at right angles with regard to the arms *l* in the stage tier above. 100

In order to exclude the current of gases 110 from the ore at the point of transfer, the upper edge *d* of the screen *b* is caused to ro-

tate within an annular member or ring *e* located in a ring *f* of stone, or like material so as to be protected against the adhesion of ore. As will be seen the ring *e* not only excludes the gas current from the roasting material, but it also enables the screen to rise in the event of an expansion of the hollow shaft.

The attachment of the individual screens 10 to the hollow shaft is effected preferably as shown in Figs. 4 and 5. Each screen carries, by means of an arm *g*, a suitably curved plate *h* adapted to fit against the shaft *c*, and provided with several, say for instance 15 four, lugs *i*. These lugs can be slipped beneath or into engagement with suitable projections *k* provided on the hollow shaft so that as the screen *b* tends to descend under the influence of gravity it becomes securely 20 fixed on the hollow shaft.

Having now particularly described and ascertained the nature of my said invention, and in what manner the same is to be performed, I declare that what I claim is:—

25 1. In a roasting furnace, in combination, a pair of superposed hearths, the upper one of said hearths being provided with an opening, a rotatable vertical shaft extending through said opening, the wall of said opening being inclined downwardly toward said shaft, an agitating arm carried by said shaft above said upper hearth to agitate the material thereon and to cause it to pass through

said opening onto the lower hearth, and a guide plate carried by said shaft and positioned below said upper hearth, said plate being inclined to the degree that the wall of said opening is inclined and forming a continuation thereof, said plate being positioned with its ore guiding surface facing 40 said shaft, whereby the ore which passes along said guide from the upper hearth to the lower hearth will be protected from the upwardly flowing gases.

2. In a roasting furnace in combination, a 45 pair of superposed hearths, the upper one of said hearths being provided with a downwardly inclined drop opening, a rotatable vertical shaft, an agitating arm carried thereby to agitate the material in said upper hearth and a screen plate carried by said shaft beneath said opening and registering thereon, said plate having a surface adapted 50 to guide the material from the upper hearth to the lower hearth, said upper hearth being 55 provided with an annular recess surrounding said opening, said plate having its upper edge projecting into said recess.

In testimony whereof I have signed my name to this specification in the presence of 60 two subscribing witnesses.

MAURICE VAN MARCKE DE LUMMEN.
